UNITED STATES PATENT OFFICE.

STEPHEN B. MORSS, OF RAHWAY, NEW JERSEY.

HYDROCARBON-LAMP.

SPECIFICATION forming part of Letters Patent No. 691,068, dated January 14, 1902.

Application filed April 20, 1899. Serial No. 713,723. (No model.)

To all whom it may concern:

Be it known that I, STEPHEN B. MORSS, a citizen of the United States, residing in Rahway, Union county, New Jersey, have invented certain new and useful Improvements in Hydrocarbon-Burning Lamps or Heaters, of which the following is a specification.

My invention relates to improvements in the class of lamps or heaters in which vapor or gas is evolved from hydrocarbon oil and commingled with air, the mixture to be burned in the form of a sootless or blue flame; and the object of my invention is to provide improvements in the devices that generate the vapor or gas.

In carrying out my invention I provide a primary combustion-chamber in which is located an oil-burner of any suitable type adapted to produce what is known as a "white flame," and in conjunction therewith I use a wick that leads to an oil-font, which wick is in proximity to or overlies said burner, so that the heat from the flame will cause vapor or gas to be evolved from the oil carried up by the wick. Said wick is protected from the flame, and by preference the wick is guided by a metallic duct or tube which is provided with one or more perforations or openings for the escape of vapor or gas, whereby the heated metal of the duct assists in evolving the vapor or gas from the oil. I also preferably surround the perforations or openings of the duct with a band of metal to prevent the flame from reaching the gases or wick. The combustion-chamber is connected with a suitable air and vapor or gas mixing chamber, to which a secondary or supplemental burner is connected in any suitable or well-known manner.

The invention also consists in the novel details of improvement and the combinations of parts that will be more fully hereinafter set forth and then pointed out in the claims.

Reference is to be had to the accompanying drawings, forming part hereof, wherein—

Figure 1 is a vertical section of a lamp embodying my improvements. Fig. 2 is a cross-section on the line 2 2 in Fig. 1; and Fig. 3 is a section substantially on the line 3 3 in Fig. 1, the shield for the burner being removed.

In the accompanying drawings, in which

similar numerals of reference indicate corresponding parts in the several views, 1 indicates a suitable oil-font, and 2 is a burner of 55 suitable construction adapted to be connected therewith, being shown provided with a perforated top 3, air-inlets 4, and a wick-tube 5, adapted to receive a wick 6, that passes into font 1, 7 being an ordinary toothed wheel for 60 controlling the wick.

8 is a shield or air-guide surrounding the upper portion of tube 5 to cause the proper burning of a flame at the end of wick 6 in well-known manner.

65 The above-described parts may generally be in any well-known or suitable construction adapted for producing a white flame from hydrocarbon oil. Above the perforated top 3 I provide a combustion-chamber composed 70 of a shell 9, that is shown resting upon the top 3, the latter having a flange or shoulder 3^a to hold the shell 9 in position, whereby the shell 9 is removable; but these parts may be otherwise arranged and connected, if desired. 75 The shell 9 is provided with an opening 9^a, adapted to be closed by a shutter or the like 10, suitably arranged thereon to permit access to the interior of the shell, as for lighting the wick 6.

80 The oil from which vapor or gas is to be produced is conducted from the font by means of a feeding-wick located in proximity to, but preferably across the top of the flame from, wick 6, and the feeding-wick is protected from the flame by a partition. For 85 these purposes I have shown a duct or tube 11, illustrated as curved at its central portion and provided with two depending leg portions that pass through the parts 2 and 3 and 90 open into the font 1, whereby a wick can be located in said tube and depend at both ends into the font. The upper surface of the tube or duct 11 at the part 11^a that crosses the top of tube 5 is provided with one or more 95 openings or apertures 11^b (see Fig. 2) for the escape of vapor or gas that is generated by the oil carried into the duct by the wick. I have shown the wick 6 as depending from tube 5 and passing over a pin or guide 12 in font 100 1, thence up through duct 11, across over tube 5, and down through said duct and depending into the font 1. By this means as the wick is consumed at the burner-tip and is fed

- forwardly new parts of the wick will be presented over the flame. It is evident, however, that separate wicks can be used—that is to say, one wick can depend from the tube 5 and the other wick can pass through the duct 11 and depend from both ends thereof, and then it can be adjusted in any convenient manner when desired. While I have shown the duct for the oil-feeding wick in the form 10 of a tube, it is evident that it can be in the form of a plate or open channel; but I prefer to use a tube, so as to avoid any danger of the oil conducted by the wick from being ignited by the flame. For the latter purpose, 15 also, when I use a tube in the form shown I preferably surround the perforations or openings with a shield, band, or collar 11^c, that extends upwardly and conducts the vapor away from the zone of the flame.
- 20 The combustion-chamber in which the vapor or gas is generated is to be connected with a vapor or gas and air mixing chamber, the latter being connected with a supplemental burner, all of which may be made in any suitable or well-known manner. I have shown 25 the shell 9 as connected by tubes 9^b with a mixing-chamber 13, shown provided with air-inlets 13^a, a burner 14 being connected with the latter.
- 30 From the foregoing it will be understood that when it is desired to produce vapor or gas from hydrocarbon oil the wick is lighted at the burner-tube 5 and the size of the flame can be regulated in well-known manner. The 35 heat from the flame will act upon the oil conducted by the wick within the heating zone of the flame in such manner as to cause vapor or gas to be evolved therefrom, and the proportion of such vapor or gas which is evolved 40 will be determined, more or less, by the size of the flame used in the combustion-chamber. The vapor or gas thus evolved passes from the duct or tube 11 through its openings 11^b up into the mixing-chamber, and it 45 is then burned at a suitable burner in the form of a sootless or blue flame either for heating purposes or for producing a light, as from a refractory mantle 15 in well-known manner.
- 50 The advantages of my improvements are that there is no necessity of smothering the flame that produces the heat for evolving the vapor or gas, and as the vapor-producing flame is not smothered the same will be strong 55 and will therefore not be liable to fluctuations due to changes in air-circulation around

the lamp, and, furthermore, the heated metal of the partition, duct, or tube 11 in contact with the oil-feeding wick will have an effect more fully to evolve the gases from the oil. 60 I thus dispense with valves and adjustable devices for feeding the oil, the auxiliary or feeding wick being automatic in its action as to the supply of oil, the height of the heating-flame regulating the quantity of vapor or 65 gas evolved.

In my improvements there is very little unconsumed products of combustion passing away from the generating or heating flame, and the chamber within band 11^c, in which 70 the vapor or gas is evolved from the feeding or auxiliary wick and allowed to escape, is almost entirely separate from the combustion-chamber.

I do not limit my invention to the precise 75 details of construction shown and described, as they may be varied, as necessity or practice may suggest, without departing from the spirit of my invention.

Having now described my invention, what 80 I claim is—

1. In a lamp or heater of the character described, the combination of a burner having a wick-tube 5, and a tube or duct having a portion overlying the wick-tube 5 and two 85 depending portions lying on opposite sides of wick-tube 5 and opening downwardly, and a wick extending continuously from wick-tube 5 to an oil-font, thence up into and through the duct and depending therefrom into the oil, the overlying portion of the duct having means to permit the escape of vapor, substantially as described.

2. In a lamp or heater of the character described, the combination of a burner having 95 a wick-tube 5, and a tube or duct having a portion overlying the wick-tube 5 and two depending portions lying on opposite sides of wick-tube 5 and opening downwardly, and a wick extending continuously from wick-tube 100 5 to an oil-font, thence up into and through the duct and depending therefrom into the oil, the overlying portion of the duct having means to permit the escape of vapor, a guide for the wick below the burner, and a shield 105 surrounding said escape means and extending upwardly, substantially as described.

STEPHEN B. MORSS.
